VENDING MACHINE

George Fargher Hight and Charles Henry Webb,
Middlesex, EnglandApplication November 9, 1934, Serial No. 752,263
In Great Britain February 27, 1933

1 Claim. (Cl. 312—51)

This invention relates to vending machines of the type adapted to be actuated by a coin-controlled apparatus and it has for its object the construction of a machine particularly adapted for vending folded articles such as newspapers, journals, magazines and the like, hereinafter generally referred to as papers, and to this end the invention consists of a casing containing a support for a pile of folded articles, means for engaging with and withdrawing the lowermost article from said pile and delivering same to a chute comprising at each end of the machine a fixed plate, a rotating plate positioned adjacent thereto, a plurality of spring actuated plungers mounted in said rotary plate, a spring actuated finger located in each of said plungers coacting with said fixed plate, and means for imparting a rotary motion to said engaging and withdrawing mechanism.

10 In the accompanying drawings which illustrate an embodiment of this invention:—

Figure 1 is a front elevation of the machine;
Figure 2 is an end elevation thereof;
Figure 3 is a front elevation, on an enlarged scale, with the cover plates removed;
Figure 4 is a section on line 4—4 of Figure 3;
Figure 5 is a section on line 5—5 of Figure 3;
Figure 6 is a section on line 6—6 of Figure 3;
Figure 7 illustrates in section a detail of construction in three different positions *a*, *b* and *c*;
Figure 8 is a front elevation of the coin-freed mechanism with certain parts removed;
Figure 9 is a section on line 9—9 of Figure 8, and
Figure 9a shows the cut-away portions of the side plates at the delivery end of the hopper.

Figure 10 is an inside view of one of the parts used in said mechanism.

In the embodiment of the invention illustrated in the drawings, which will be described for use in delivering papers, the support for the papers *X* comprises an adjustable base plate *1* secured to the top of two end plates *2*, said base plate being of any desired width and depth according to the size of the papers to be supported thereon, and a vertically disposed hopper like member *3* having two side walls a back and a removable front plate *3a* and the front edges of the side members are each provided with a narrow strip *4* disposed parallel with the back plate and furnished at their lower ends with a retaining strip *5* capable of being adjusted vertically so as to provide means for varying a gap *6* between the lower edges of said members and the base plate *1* according to the thickness, preferably folded

once or twice, of a single paper. The supporting guide for the papers as they are drawn from the pile, in the manner hereinafter described, extends from the front edge of the base plate *1* somewhat in the form of a drum *7* so that as said papers are freed from the withdrawing means they fall into a chute *8* provided in the front of the main casing *9*.

The means for withdrawing the papers *X* from the hopper *3* comprises a plurality of withdrawing fingers (hereafter more fully described) carried by two circular plates *10* secured as at *11* on a shaft *12*, hereinafter referred to as the driven shaft, extending from one side of the machine to the other, said shaft being rotatably mounted in plates *13* and in cam plates *14* rigidly secured to the plates *13*. The plates *2* and *13* are secured to a base board *15*, the supports of which are secured to the bottom of the main casing *9*. The plates *10* are each provided with say three longitudinally disposed bosses *16* in each of which is secured a double acting plunger disposed parallel to the axis of the shaft *12*, each of said plungers comprising, as shown in Figures 7 (a), (b) and (c) a hollow plunger *17* slidably arranged in a bore *18* provided in each of the bosses *16*; a spring *19* arranged to operate between the inner end of the bore *18* and the outer face of a plug *20* secured in the inner end of the plunger *17*, a further plunger *21* carrying a rod or finger *22* located in said plunger, said fingers being above referred to as the withdrawing fingers, adapted to slide in the plug *20* and to project through an aperture *18x* provided at the inner end of the bore *18*, said withdrawing finger being pressed into the partly projected position by a spring *23* located within the plunger *17*, when the latter is pressed inwardly as hereafter described and as shown in Figure 7 (b), against the outer faces of the plates *2* from which an annular strip extending from a point just beyond the centre at the top down the front to a point *2x* (Figure 5) is removed, and the top vertical edge *2a* is cut back as shown at *2x* in Figures 5, 7 (c) and 9 but more clearly in Figure 9a.

Arranged adjacent to and parallel with the outer flat face of each of the plates *13* is arranged one of the cam plates *14* above referred to, each of which is furnished on the face adjacent the plate *10* with an annular cam surface *24* against which the outer ends of the plungers *17* or parts secured thereto are arranged to slide.

A type of coin-freed mechanism for use with the machine as above described will now be re-

ferred to, with particular reference to Figures 8, 9 and 10.

The cam plate 14 at one end of the machine is furnished on its outer face with an annular ring 25 forming in the centre of said cam plate a shallow circular recess in which a flat disc 26, hereinafter referred to as the driven disc, is located and adapted to rotate, said driven disc being provided on that face adjacent the plate 19 with a centrally disposed boss 26^a and set screw 26^b by means of which the driven disc is secured to the shaft 12. The outer face of the driven disc 26 is provided with three projecting studs 27 (Figure 8) equally spaced apart and located at a distance from the outer edge of the plate accordance to the diameter of the coin 28 to be used in the machine. A further circular disc 29, hereinafter referred to as the driving disc, of the same diameter as the driven disc 26, is placed against the latter, said driving disc being provided on its outer face with a boss 30 adapted to be mounted in a bearing 31 forming part of a cross plate 32 secured at each end to the face of the plate 13. The inner face of the driving disc 29 is provided with an annular groove 33 coincident with the studs 27 on the driven disc, as indicated in Figures 8 and 10; said inner face is also provided with a groove 34, hereinafter referred to as the coin-groove, extending from one side of the disc to the other; one edge of the said coin-groove is straight and passes slightly to one side of the centre (Figure 10); the other edge is shaped so that the width of the groove at the centre is less than at the extreme ends. The width of the coin-groove at the entry end 34^a is approximately equal to the diameter of the coin 28; a stud 35 projecting from the inner face of the driving disc is provided for limiting the extent to which a coin of the correct value enters the coin-groove, the arrangement being such that said coin enters slightly below the peripheral edge of the discs 26 and 29.

The annular ring 25 which forms the recess in which the driving and driven discs above described are located, is slotted or cut away circumferentially approximately to the width of the coins to be used as at 36, and also at the bottom as at 37 to a somewhat greater extent. Immediately above the cut away portion 36 and secured to the plate 13 is arranged a coin-chute 38 through which the coins 28 pass from the outside to the coin-groove 34 between the discs; a further coin-chute 39 is disposed below the cut away portion 37 into which the coins 28 pass from the coin-groove to the drawer 40 arranged beneath same.

The extreme end of the boss 30 on the disc 29 passes through the side wall of the main casing 9 and a handle 41 is secured thereto by the grub screw 42. The handle 41 and the driving disc 29 are only intended to have a partial rotative movement and to limit and determine the degree of rotation, a stop plate 43 is secured to the side wall of the casing and means are preferably provided for returning the handle 41 to its starting position as shown by the full lines in Figure 2 and such means may consist (as more clearly shown in Figure 6) of a spring 44 arranged to seat in a channel formed in an annular ring 45 provided on the outer face of the driving plate 29, one end of said spring being anchored to a pin 46 secured in the driving plate 29, the other end of said spring being anchored to a pin 47 secured in the base board 15.

The entire mechanism and paper support are

contained within the casing 9 with the exception of the operating handle 41, and so that it may be possible to see whether there are papers in the machine or not, the front plate 3^a of the hopper 3 coincident with and above the paper support is preferably provided with a transparent window 48, said plate being secured in position by a lock 49 and the drawer 40 by a lock 50.

To enable the plate 3^a to be removed to permit folded papers to be placed on the base plate 1, the lock 49 is turned to withdraw the bolt 53 thereby enabling the top edge of the plate 3^a to pass upwardly to an extent sufficient to permit the lower edge of said plate to pass above the top edge of the casing 9.

The operation of the machine will now be briefly described.

Assuming the handle 41 is in such a position that the entry end 34^a of the coin-groove 34 in the driving disc 29 is coincident with the slot 36 in the annular ring 25 and coin-chute 38, a coin 28 is inserted in the slot 51 in the main casing and drops through the coin-chute 38 into the coin-groove 34 where its fall is limited by the stud 35 on the driving disc 29; if the handle 41 is now pulled forward, the driving disc is turned until the coin comes against a stud 27 on the driven disc 26 thereby locking the two discs together and preventing any independent rotation of one disc apart from the other in a forward direction. Continued movement of the handle and the discs in the same direction rotates the driven shaft and thereby the plunger carrying plates 10; this rotative movement brings one pair of oppositely disposed withdrawing fingers 22, the track line of which, on the plates 2, is indicated by the heavy broken line 52 in Figure 9a to the cut away part 2^x, which is adjacent the front edge of the folded paper, where said fingers, (which are in the position shown in Figure 7 (b)) having passed from the plate 2 which maintained same in the retracted position, are simultaneously ejected into the folds of the paper (position Figure 7 (c)); further rotation of the handle 41 causes the fingers 22 to withdraw the lowermost paper X from the base 1 (Figure 3), any papers immediately above being prevented from following by the retaining strips 5 on the front edges of the hopper like member 3, until it is discharged from the fingers to the delivery chute 8, and simultaneously with this the fingers 22 are withdrawn into the position shown in Figure 7 (a) by reason of the fact that the ends of the hollow plungers 11 have passed from the highest point of the cam surfaces 24 to the lowest (position Figure 7 (a)). When the parts reach this position the coin drops from the coin-groove and through the slot 37 in the bottom of the annular ring 25 into the chute 39 and into the drawer 40, leaving the handle 41 and thereby the driving disc 29 free to be returned, in the reverse direction, to the first position. The arrival of one pair of withdrawing fingers at the discharge position also causes a second pair to arrive adjacent the position (Figure 5) where they will be ready to engage the next paper on the insertion of a further coin and the repetition of the operation.

It will be understood that the number of withdrawing fingers and the number of studs on the driven plate of the coin-free mechanism may be varied as desired according to the amount of travel required and necessitated by the size of the paper.

If an attempt is made to insert a coin of incor-

fect size or value in the coin slot, said coin will either not enter the coin-chute or coin-groove or it will pass straight through both to the coin receptacle.

5 It will be further understood that while the invention has been described with particular reference to the delivery of folded articles such as newspapers, magazines and the like, it may also be employed in machines for delivering other articles capable of being folded and packed one above the other, such as towels.

10 What we claim is:—

15 In a vending machine for the purpose described, the combination with a casing including an article container, a support for a pile of folded articles, means for engaging with the

5 folds of the lowermost article and drawing the same from beneath the pile including, at each end of the machine, a non-rotating cam plate, a rotary plate positioned adjacent thereto, a plurality of spring actuated plungers mounted in said rotary plate, a spring actuated finger located in each of said plungers coacting with said cam plate, means for preventing the ejection of said fingers during a part of their travel, a shaft upon which said rotary plates are secured rotatably mounted in said cam plates, and means for imparting a rotary movement to said shaft and to the rotary plates.

10 GEORGE FARGHER HIGHT. 15
CHARLES HENRY WEBB.
